H. KRONKE

SUGAR DISPENSER

Filed Nov. 5, 1925

UNITED STATES PATENT OFFICE.

HEINRICH KRONKE, OF BALTIMORE, MARYLAND.

SUGAR DISPENSER.

Application filed November 5, 1925. Serial No. 67,131.

The present invention relates to dispensing devices, and more particularly to a device for dispensing sugar and the like.

An object of the present invention is to provide a holder for sugar which may be used in public places, such as in restaurants, and which is adapted to contain a quantity of sugar and protect it from the air and from access of dust and other foreign particles that are frequently admitted to sugar bowls and the like, and to provide means for delivering the sugar in measured quantities for use.

Another object of the invention is to provide a receptacle or jar for sugar with a removable top serving as a housing for measuring and dispensing means of a nature which may be easily operated by one finger of the hand employed for inverting the jar, in a manner for dispensing the sugar.

The invention further aims at the provision of a dispenser of this character which has but one movable part which combines inlet and outlet closures, the measuring receptacle, and also the neck or spout through which the contents may be poured, the single member being housed within a cap out of contact with the dust and surrounding air and also in position such that it can not be handled.

The invention also provides a device which may be easily fastened upon the upper end of different types of jars and which is operable by inverting the jar and subsequently pushing a small thumb or finger lever for a short distance, and which may be accomplished by the same hand which carries and holds the jar.

A still further object of the invention is to provide a combined measuring and dispensing device of this type which may be economically manufactured as it may be made of sheet metal and comprises but very few parts, and a device which can not easily get out of order.

The above and various other objects and advantages of this invention will in part be described in and in part be understood from the following detailed description of the present preferred embodiment, the same being illustrated in the accompanying drawing, wherein:

Fig. 1 is a side elevation of a sugar dispenser constructed according to the present invention.

Fig. 2 is an enlarged horizontal section taken through the top of the same and showing the device in position for delivering a charge of the sugar.

Fig. 3 is a fragmentary inverted vertical section through the upper end of the device in the position shown in Fig. 2, and showing the contents being delivered from the measuring receptacle.

Fig. 4 is a similar view showing the parts adjusted for closing the outlet opening and for filling the measuring receptacle from the jar or container, and

Fig. 5 is a perspective view showing the inner wall or disk and the movable member 70 slidably thereon, the dotted lines illustrating the container and the cap in relative positions to the same.

Referring to the drawing 10 designates a receptacle or container provided upon its upper end with an externally threaded neck 11 over which is detachably secured a closure cap 12. The cap 12 has a screw threaded flange or skirt 13 which preferably flares outwardly at its lower edge and is detachably engaged upon the neck 11. The receptacle or container 10 may be of any suitable size, configuration or material to meet conditions and the flange 13 is correspondingly modified to fit the receptacle.

The cap 12 is relatively deep to provide a chamber therein which extends beyond the neck 11 and has an outer closure wall 14 provided at a suitable point with an outlet opening 15 establishing communication between the interior of the cap and the outside atmosphere. A disk 16 is fitted in the inner end of the cap 12 and is adapted to seat against the upper or outer edge of the neck 11. The disk 16 is provided at suitable points about its peripheral edge portion with upstanding spacer bars or ribs 17 adapted to lie against the inner side of the cap 12, and which may be secured thereto by screws 18 or the like.

The disk 16 is provided with a filler opening 19 at a suitable point offset from the opening 15 in the cap. Mounted in the chamber of the cap between its top wall 14 and the disk 16 is a slidable or movable member in the form of a receptacle 20 which is preferably shaped to the configuration of the openings 15 and 19 and which extends between the wall 14 and the disk 16 and is adapted to be closed at opposite ends 110

by contact with the wall and the disk. The receptacle 20 carries at one side and at one end a flat leaf or slide 21 arranged to traverse the inner side of the wall 14, and is provided at its other end and at its other side with a second leaf or slide 22 adapted to slidably engage the inner side of the disk 16.

The movable member is provided at preferably its outer end and at one side with an extension 23 preferably lying in the plane in the leaf 21 and forming a part thereof and which has an aperture 24 for receiving a pivot 25 secured to the outer wall 14 of the cap. This pivot 25 holds the movable member in the cap and permits the swinging of the movable member back and forth on the pivot. The other side of the movable member has a thumb or finger lever 26 which projects outwardly through a longitudinal slot 27 formed in the cap 12 to permit access to the outer end of the lever 26. A spring 28 is mounted at one end on the lever 26 within the cap 12 and at its other end is secured to an adjacent spacer bar 17, the spring normally drawing the lever 26 toward the spacer bar and into one end of the slot 27. The parts are so relatively placed that the spring 28 normally and yieldingly maintains the receptacle 20 in register at its inner end with the filler opening 19, and with the outer shutter or slide 21 covering the outlet opening 15.

When the receptacle 10 is in upright position as shown in Fig. 1, no dust or foreign particles may enter the cap 12 as the slide 21 keeps the opening 15 closed. As soon as the receptacle is inverted the sugar or other contents of the receptacle 10 is poured through the filler opening 19 into the measuring container 20. While inverted, when the lever 26 is moved against the tension of the spring 28 into the remote end of the slot 27, the inner shutter 22 is drawn across the filler opening 19 to close it and the shutter 21 is moved from the opening 15 and the outer end of the measuring receptacle 20 is brought into register with the outlet opening 15. The inner end of the receptacle 20 is thus closed by the disk 16 while the contents within the measuring receptacle is permitted to flow through the outlet opening 15.

Each reciprocating movement of the member 20 first discharges the material in the receptacle 20 and subsequently moves the receptacle back into position for receiving a new charge. As the openings 15 and 19 are offset, the offset shutters or slides 21 and 22 are moved to alternately open and close the openings 15 and 19.

There is thus but one movable element in the cap which provides the two valves and the measuring receptacle, the spring 28 serving to operate this single movable member.

It is of course understood that various changes and modifications may be made in the details of construction and design of the above specifically described embodiment of this invention without departing from the spirit thereof, such changes and modifications being restricted only by the scope of the following claims.

What is claimed is:

1. A dispensing device of the class described comprising a container, a closure cap for the container including inner and outer spaced walls forming a chamber, said inner and outer walls each having an opening therethrough with the opening of one wall disposed in offset relation with the opening of the companion wall, and a measuring member pivotally mounted at one end in the chamber to one side of the axial center of the chamber, including a receptacle having open opposite ends for alternate aligning with said openings and shutter plates at each end of the receptacle and in contact with the cap walls for alternate closing of said openings when the receptacle is swung out of register therewith.

2. A dispensing device of the class described comprising a container, a closure cap for the container including inner and outer spaced walls forming a chamber, said inner wall being provided with an inlet opening communicating with the container and said outer wall having an outlet opening communicating exteriorly of the closure cap and disposed in offset relation to the filler opening and intersected by the axial center of the closure cap, a measuring member pivotally mounted at one end in the chamber to one side of the axial center of the chamber, including a receptacle having open opposite ends for alternate aligning with said openings and oppositely offset shutter plates at the open ends of the receptacle in contact with said closure cap walls for alternate closing of said filler and outlet openings when the receptacle is swung out of register therewith, and spring means normally urging the measuring member to a position with the receptacle registering with the filler opening of the inner wall and the offset shutter plate at the outer end of the receptacle closing the outlet opening of the outer closure cap wall.

3. A dispensing device for detachable connection with a container, comprising a cap having a skirt portion at one end for attachment to the container and having a wall closing its outer end provided with an outlet opening intersected by the axial center line of the cap, a disc mounted in the cap and having spacing bars engaging the outer wall of the cap for spacing the disc therefrom and providing a chamber, said disc being provided with a filler opening offset from the outlet opening of the cap, a meas-

uring member pivotally mounted at one end to the disc to one side of the axial center of the disc and including a receptacle having open opposite ends slidably engaging said wall and disc for alternate aligning with said openings, oppositely offset shutter plates at the open ends of the receptacle in contact respectively with said disc and cap wall for alternate closing of said openings when the receptacle is swung out of register therewith, and a finger lever extend-
5 ing from the receptacle and projecting through a circumferentially extending slot provided in the cap, and a spring connecting said lever and cap for normally moving the 15 lever to a position at one end of said slot for normally retaining the receptacle in registry with the filler opening of the disc and with the shutter plate at the outer end of the receptacle closing the outlet opening 20 in the end wall of said cap.

HEINRICH KRONKE.
